Primary Examiner—Bruce W. Dunkins
Attorney, Agent, or Firm—Davidson C. Miller

[57] **CLAIM**

The ornamental design for a table, as shown and described.

DESCRIPTION

FIG. 1 is a view in side elevation of a table showing my design.

FIG. 2 is an end view thereof;

FIG. 3 is a plan thereof;

FIG. 4 is a perspective view thereof.

The side and end not shown in FIGS. 1 and 2 are mirror images of the side and end shown respectively.
